[73] Assignee: **Par Industries, Inc.**, Medina, Ohio

[57] CLAIM

[**] Term: 14 Years

The ornamental design for a protective cover for play gym leg joints, as shown and described.

[21] Appl. No.: 646,052

DESCRIPTION

[22] Filed: Jan. 25, 1991

FIG. 1 is a perspective view of a protective cover for play gym leg joints showing our new design;

[52] U.S. Cl. D21/242

FIG. 2 is a perspective view thereof, shown in an alternate position;

[58] Field of Search D21/240, 242, 243, 244,

FIG. 3 is a top plan view thereof; the bottom plan view being a mirror image thereof;

D21/245; 403/362, 202, 203, 220, 223, 405.1;

FIG. 4 is a left side elevational view thereof; the right elevational view being a mirror image thereof; and,

52/5, 3, 645, 650, 659, 665, DIG. 6; D25/61,

FIG. 5 is a front elevational view thereof; the rear elevational view being a mirror image thereof.

68, 129, 133

The broken line showing of the legs for a play gym is for illustrative purpose only and forms no part of the claim.
